UNITED STATES PATENT OFFICE

144,038

DESIGN FOR A SHOE CLOG

John H. Davis and Gerald McAllister,
Los Angeles, Calif.

Application October 16, 1945, Serial No. 123,517

Term of patent 14 years

(Cl. D7—5)

To all whom it may concern:

Be it known that we, John H. Davis and Gerald McAllister, citizens of the United States and residents of Los Angeles, California, have invented a new, original, and ornamental Design for a Shoe Clog, of which the following is a specification reference being had to the accompanying drawing, forming a part thereof:

Fig. 1 is a side elevational view of a shoe clog showing our new design.

Fig. 2 is a top plan view.

We claim:

The ornamental design for a shoe clog, as shown.

JOHN H. DAVIS.
GERALD McALLISTER.
